UNITED STATES PATENT OFFICE.

WILLIAM H. SNYDER, OF CANTON, OHIO, ASSIGNOR OF ONE-HALF TO
CHARLES R. MILLER, OF SAME PLACE.

DARNING-LAST.

SPECIFICATION forming part of Letters Patent No. 664,104, dated December 18, 1900.

Application filed April 9, 1900. Serial No. 12,057. (No model.)

To all whom it may concern:

Be it known that I, WILLIAM H. SNYDER, a citizen of the United States, residing at Canton, in the county of Stark and State of Ohio, 5 have invented new and useful Improvements in Darning-Lasts, of which the following is a specification.

My invention relates to improvements in darning-lasts, and has for its objects the providing of a last with a slightly-convexed top merging into circumferential vertical sides extending around the last and adapted to receive a retaining-band to hold the goods in position and also in providing a hollow handle terminating in a plug likewise provided with a slightly-convexed top, as will be hereinafter more fully described and claimed.

Figure 1 is a perspective view of my invention. Fig. 2 is a longitudinal central section 20 of the same. Fig. 3 is a perspective view of the retaining-band.

In the accompanying drawings similar letters of reference refer to similar parts.

A represents a darning-last, which may be 25 made of wood or other light material, the top B being slightly convexed for the purpose of forming the darning-surface and enabling the needles to be more readily turned and passed through the material. The top B merges into circumferential vertical sides C, extending around the last, which is adapted 30 to receive the retaining-band D, which may be made of light-weight steel, wood, hard rubber, or any other suitable material having 35 a permanent or fixed form as distinguished from soft rubber or elastic material. The handle E is hollow, thus forming a needle-receptacle F, and is adapted to be closed by the plug G, the outer surface of which is convexed, so as to form a second darning-surface H for small articles.

In operation the matter to be darned is loosely placed over the top B of the darning-last and the retaining-ring D slipped over 45 and upon the vertical side C of the last, when it will be found that the goods to be operated upon are drawn up into a desirable position to receive and permit of the passage of a needle therethrough. At the same time, by reason 50 of the clamping of the goods around the vertical sides of the last, by means of the re-

taining-band the goods are held firmly in position, and the last is more conveniently and easily held by the operator, because of the narrow and extended handle thereof.

55

I am aware that heretofore there have been provided darners of a substantially conical form provided with circumferential grooves and elastic rubber bands for retaining the goods in position; but these devices have not 60 been practical, for the reason that the shape was such that it could not be readily held or handled by the operator, the elastic bands would stretch and become lost, and the position of the goods could not be changed while 65 on the last without entirely removing the rubber or elastic band.

I am also aware that darning-lasts have been provided consisting of a substantially spheroidal form truncated at the bottom and 70 terminating in a hollow handle to receive the needles; but these lasts have been provided also with a conical darning-surface at the top and with no means of retaining the goods upon the last other than the grip of the operator; but this device does not accomplish 75 the objects of my device, for the reason that it does not present a convexed surface, so essential to the proper operation of darning, nor does it provide a means for holding the 80 goods upon the last.

I am also aware that an embroidery-cushion has been provided having a hollow stem and casing open at the top and provided with an elastic brush-cushion seated therein and having 85 a circumferential groove around its side adapted to receive an elastic band; but this device does not accomplish the object of my device, for the reason that the brush-cushion does not provide a satisfactorily-convexed 90 surface by which the goods can be held in position and the needles turned or guided in the work, and there is no provision for a needle-holder, and the goods to be operated on are so held upon the darning by reason of the elastic band entering the circumferential groove and holding the goods against the edges thereof that it cannot be adjusted from time to time without entirely removing the band.

Having thus fully described my invention, 95 what I desire to secure and claim by Letters Patent is—

The herein-described darning-last, the same comprising a cylindrical body terminating at one extremity in a reduced handle portion, and at the other extremity in a smooth convex surface, and having a curved flat open-ended retaining-spring for engaging closely said cylindrical body, substantially as and for the purpose set forth.

In testimony whereof I have hereunto set my hand in the presence of two subscribing witnesses.

WILLIAM H. SNYDER.
